FOLDABLE WALL SHELVING UNIT

James S. Moore, 1601 Rambla Pacifico,
Malibu, Calif. 90265

Filed June 29, 1970, Ser. No. 23,746

Term of patent 14 years

Int. Cl. D6—06

U.S. CL. D6—130

FIG. 1.

FIG. 3.

FIG. 2.

FIG. 1 is a perspective view of a foldable wall shelving unit showing my new design;

FIG. 2 is a perspective view thereof, showing the shelves in their open position; and

FIG. 3 is a side elevational view taken from one side thereof.

I claim:

The ornamental design for a foldable wall shelving unit, as shown and described.
